Primary Examiner — Kevin Rudzinski*(74) Attorney, Agent, or Firm* — Heslin Rothenberg Farley & Mesiti P.C.(57) **CLAIM**

The ornamental design for a light fixture, as shown and described.

DESCRIPTION

FIG. 1 is a perspective view of the light fixture of the present design;

FIG. 2 is a front elevation view thereof;

FIG. 3 is a right-side elevation view thereof;

FIG. 4 is a rear elevation view thereof;

FIG. 5 is a left-side elevation view thereof;

FIG. 6 is a top plan view thereof;

FIG. 7 is a bottom plan view thereof; and,

FIG. 8 is an enlarged front elevation view thereof with additional environmental structure.

The broken lines in the drawings illustrating unclaimed portions of the design and environmental structures form no part of the claimed design.

The overall shape of the suspended crystal-like elements is claimed but the facets shown in broken lines form no part of the claimed design. The location of each suspended crystal-like element about the corresponding support strand is random.
